UNITED STATES PATENT OFFICE

EDWARD J. ZAHNER, OF LA PORTE, INDIANA, ASSIGNOR TO METAL DOOR & TRIM CO.,
OF LA PORTE, INDIANA

LOUVER-DOOR STRUCTURE

Application filed May 23, 1928. Serial No. 279,901.

The invention relates to louver door structures, and has for its object to provide a device of this character wherein the louver is carried by a panel formed from registering plates between which flanges of the louvers extend and are secured, which flanges are in vertical planes, and angle members carried by the inner edges of said plates, and with which the outer flanges of the louvers engage, thereby bracing the louvers and at the same time forming a finish for the ends of the louvers.

A further object is to dispose the edges of the panels in a channel of a molding, which molding has an interlocked engagement with a member carried by the stiles and rails of the door, thereby allowing the panel with the louvers therein to be easily and quickly assembled within the door as a panel unit.

20 A further object is to provide the ends of the louvers with centrally disposed extension arms in vertical planes, which arms extend between the panel plates and are secured thereto, for instance by spot welding.

25 A further object is to provide the inner edges of the panel plates with oppositely extending angle portions, which portions reinforce the inner edges of the panel and also form a marginal frame for the plurality of louver slats.

30 A further object is to provide louver slats having vertical portions and upwardly and downwardly inclined flanges terminating in upwardly and downwardly extending flanges in vertical planes whereby when said slats are placed in overlapped relation a maximum ventilating space is formed therebetween, and one which will direct air upwardly to one side of the louver or downwardly at the other in its passage through the louver.

35 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

40 In the drawing:

Figure 1 is a view in elevation of the door, showing the louver applied thereto.

Figure 2 is a perspective sectional view taken on line 2 of Figure 1.

Figure 3 is a horizontal sectional view 55 through the side of the door taken on line 3 of Figure 1.

Figure 4 is a perspective view of one end of one of the louver slats.

Referring to the drawing, the numeral 1 designates the stiles of the door and 2 the rails thereof. Mounted on the rails and stiles is a sheet metal molding 3, which molding is provided with a channel 4, which extends into the rails and stiles and is held between 65 spring flanges 5 of the channel members 6 carried by the rails and stiles, there being an interengagement at 7. Disposed within the channel member 4 is the panel 8 which carries the louver. Therefore it will be seen that 70 the louver and panel are formed as a single unit to be assembled in the door. The panel 8 comprises registering plates 9, preferably having a metallic covering 10, and the inner edges of said plates 9 are provided with outwardly extending flanges 11 terminating in inwardly extending flanges 12, thereby forming right angled members extending in opposite directions on opposite sides of the panel. The lower louver slat 13 is provided 75 with an extension flange 14, which is disposed between the panel plates 9, and is secured therebetween for instance by spot welding at 15, therefore it will be seen that the louver slat 13 will be rigidly held. The intermediate slats 16 have their central vertically disposed portions 17 provided with extensions 18, which extensions extend between the plates 9 of the panel at the sides thereof, and are securely held in place by spot welding 80 at 19, therefore it will be seen that the ends of the slats are rigidly held. The upper and lower edges of the vertical portions 7 of the intermediate slats 16 terminate in upwardly and downwardly inclined flanges 20, which 85 extend towards the flanges 12 of the panel and are provided with upwardly and downwardly extending vertical flanges 21, which engage the inner sides of the flanges 12, and are secured thereto by spot welding if so 90

100

desired. The flanges 20 and 21 have their ends in abutting engagement with the flanges 11 carried by the panel plates 9, therefore it will be seen that the ends are concealed from view, are rigidly braced and the flanges 12 form a finish for the louver of the door, which does not detract from the appearance of the door as is obvious by referring to Figure 1.

10 The lower louver slat 13 at its upper edge terminates in an upwardly and outwardly inclined flange 22, which in turn is provided with a vertically disposed flange 23 in the same vertical plane as the slat flange 21, therefore it will be seen that the slat flanges 21 and 23 are in parallel planes which will not only add depth to the louver as a whole, but will also form air passages which will deflect air upwardly and downwardly into 15 and out of a room, but will exclude or prevent a person from seeing through the louver into a room.

From the above it will be seen that a door is provided with a panel carried louver, which 20 may be easily and quickly assembled within the metallic door and which panel may be received in the usual metallic molding of doors of this character, thereby allowing the units to be assembled in the doors during construction in the same manner as a conventional form of panel.

The invention having been set forth what is claimed as new and useful is:—

1. The combination with a metallic door frame, a panel disposed in said frame, said panel being formed from registering plates, a plurality of louver slats having their ends secured between the registering plates, and angular flanges extending from said slats.

2. The combination with a metallic door, a panel molding carried thereby, a panel disposed in said molding, said panel comprising registering plates, louver slats, said louver slats having portions extending between the registering plates of the panel and secured thereto, oppositely extending angular flanges carried by the plates, said louver slats having offset flanges in vertical planes engaging the angular flanges of the plates.

3. A metallic door structure comprising a frame, a molding carried by said frame, a panel having a louver opening therein, said panel being formed from registering plates disposed in the molding, the inner edges of said registering plates being provided with outwardly and inwardly extending integral flanges, louver slats secured between the plates and in the same plane, said slats having upwardly and downwardly inclined flanges extending in opposite directions, said flanges terminating in vertically disposed flanges engaging the inwardly extending portions of the integral flanges carried by the registering plates of the panel.

4. The combination with a louver opening

extending through a panel, of means for securing louver slats in said opening, said means comprising forming the panel from registering sections, said louver slats being secured between the registering sections of the panel, 70 the inner edges of said registering sections having marginal angular flanges extending inwardly in relation to the opening in the panel, louver slats within said opening, the bodies of said louver slats having their ends secured between the registering sections of the panel, said louver slat bodies having angularly disposed flanges, said angularly disposed flanges engaging the angularly disposed flanges of the panel plates. 75

5. An article of manufacture, a louver panel formed from registering plates having openings therethrough, louver slats having portions secured between the registering plates, the marginal edges of said openings 80 through the registering plates being provided with offset flanges and offset flanges carried by the louver slats and engaging the offset flanges of the plates.

6. A louver panel formed from plates having 90 openings therethrough, said plates having offset flanges around the openings therein, louver slats in said openings, said slats having centrally disposed portions in a vertical plane and secured between the panel plates, 95 said slats having offset portions engaging the offset flanges of the panel plates.

7. An article of manufacture, a louver panel comprising registering plates having marginal off-set portions, a plurality of slats 100 having their ends secured between said registering plates, and flanges extending from said slats and between said marginal off-set portions in overlapping relation to the adjacent slats.

8. An article of manufacture, a louver panel comprising registering marginal plates having off-set flanges, and louver slats having their ends secured between said plates, said slats having flanges projecting 110 therefrom within the planes of said off-set flanges.

9. An article of manufacture, a louver panel comprising registering marginal plates having oppositely directed off-set flanges 115 formed on the inner edges thereof, and louver slats having the ends secured between said plates, said slats having flanges projecting therefrom within the planes of said off-set flanges.

10. An article of manufacture, a louver panel comprising registering marginal plates having oppositely directed off-set flanges formed in the inner edges thereof, and louver slats having their ends secured between said plates, said slats having oppositely directed off-set flanges projecting therefrom within the planes of said off-set flanges. 125

11. A door panel comprising registering margin plates having off-set flanges on the 130

inner side thereof forming a channel, louver slats having their ends secured between said plates, oppositely directed inclined flanges carried by said slats, and vertical flanges carried by said inclined flanges, the inclined and vertical flanges of adjacent slats being disposed in overlapping relation.

In testimony whereof I affix my signature.
EDWARD J. ZAHNER.
